CLAIM

The ornamental design for the faucet body and spout, as shown and described.

DESCRIPTION

FIG. 1 is a front perspective view of a faucet body and spout showing our new design;

FIG. 2 is a rear perspective view thereof;

FIG. 3 is a top plan view thereof;

FIG. 4 is a front elevational view thereof;

FIG. 5 is a rear elevational view thereof;

FIG. 6 is a left side elevational view thereof;

FIG. 7 is a cross-sectional view of the spout taken along line 7—7 in FIG. 6;

FIG. 8 is a right side elevational view thereof;

FIG. 9 is a left side elevational view of a modified form of the faucet body and spout shown in FIG. 1;

FIG. 10 is a cross-sectional view of the spout taken along line 10—10 in FIG. 9;

FIG. 11 is a front elevational view of the modified form of the faucet body and spout shown in FIG. 9;

FIG. 12 is a rear perspective view of the modified form thereof;

FIG. 13 is a front elevational view of a second modified form of the faucet body and spout shown in FIG. 1;

FIG. 14 is a left side elevational view of the second modified form of the faucet body and spout shown in FIG. 13; and, FIG. 15 is a cross-sectional view of the spout taken along line 15—15 in FIG. 14.

The broken line showings of a handle and aerator in FIG. 1 are for purposes of illustration only and form no part of the claimed design.
